CLAIM

The ornamental design for a faucet handle and body, as shown and described.

DESCRIPTION

FIG. 1 is a front, top and right side perspective view of a faucet handle and body showing my new design;

FIG. 2 is a front elevational view of the faucet handle and body shown in FIG. 1;

FIG. 3 is a back elevational view of the faucet handle and body shown in FIG. 1;

FIG. 4 is a top plan view of the faucet handle and body shown in FIG. 1; and,

FIG. 5 is a left side elevational view of the faucet handle and body shown in FIG. 1, the right side view being a mirror image of the left side.
